A. W. GREGOR AND T. H. FRENCH.
LAMP BURNER.
APPLICATION FILED MAY 6, 1918

1,312,478.

Patented Aug. 5, 1919.

UNITED STATES PATENT OFFICE.

AUGUST W. GREGOR, OF MERIDEN, CONNECTICUT, AND THEODORE H. FRENCH, OF CHICAGO, ILLINOIS, ASSIGNEES, BY MESNE ASSIGNMENTS, TO THE MANTLE LAMP COMPANY OF AMERICA, OF CHICAGO, ILLINOIS, A CORPORATION OF ILLINOIS.

LAMP-BURNER.

1,312,478.

Specification of Letters Patent. Patented Aug. 5, 1919.

Application filed May 6, 1918. Serial No. 232,776.

To all whom it may concern:

Be it known that we, AUGUST W. GREGOR and THEODORE H. FRENCH, citizens of the United States, residing at Meriden, in the 5 county of New Haven and State of Connecticut, and Chicago, in the county of Cook and State of Illinois, respectively, have invented a certain new and useful Improvement 10 in Lamp-Burners, of which the following is a full, clear, concise, and exact description, reference being had to the accompanying drawings, forming a part of this specification.

Our invention relates to improvements in 15 burners, and has special reference to burners adapted for hydro carbon oils, such as kerosene and for use with mantles which are heated in to incandescence for the production of light.

20 This type of burner is commonly known as the "blue flame" burner, as the greatest efficiency in the production of light by means of a mantle is obtained when the fuel is most efficiently burned for the production 25 of heat and not for light directly.

It is well known that a blue flame, which indicates that there is no free carbon being given off or produced, also indicates the most efficient combustion of the fuel.

30 The object of our invention is to provide a burner of the character described, by which greater efficiency shall be obtained than heretofore has been possible, it shall be capable of adjustment from maximum to 35 minimum production of light without the flame changing from a blue or non-luminous to a yellow or luminous flame; and which shall result in the burner being maintained at a minimum temperature for all heights 40 of flame.

Our invention resides in a burner of the tubular wick or so-called Argand type, provided with means for causing such a perfectly controlled projection of the air into 45 the flame of the burner, at all points of adjustment of the wick, that perfect combustion of the carbon contents of the fuel ensues that all possibility of the production of free carbon is eliminated and that the fuel is 50 burned at a maximum of efficiency.

Our invention also consists in the combinations and arrangements of parts and devices and in the several features of construction by

which we are enabled to attain the above described and other objects and all as herein- 55 after described and particularly pointed out in the appended claims.

Our invention will be more readily understood by reference to the accompanying drawing forming part of this specification 60 and in which:

Figure 1 is a side elevation of a mantle lamp embodying our invention in one preferred form;

Fig. 2 is an enlarged fragmentary vertical 65 section view of the burner part of the lamp;

Fig. 3 is an enlarged vertical central section of the inner air distributer or spreader; and

Fig. 4 is an enlarged fragmentary vertical 70 sectional view of the upper end of the wick and the coöperating burner parts.

We have illustrated our invention as best exemplified by its application to a central draft or Argand burner which uses a tubular 75 wick and produces a round or circular flame. The air for a flame of this character is supplied by air supply passages both within and without the wick.

This form of wick is especially adapted 80 in shape for use with a suitable mantle. The old Argand burner without a mantle, but producing a white or luminous flame, was fairly efficient, though it was at times difficult to maintain the burner properly adjusted. This difficulty of adjustment was greatly enhanced upon the application of the mantle and the attempt to adjust the burner to produce a blue flame for heat instead of a 85 luminous flame for light. And further, it has, before our invention, been impossible, so far as we have been able to learn, to adjust a mantle burner of this form from maximum light to minimum light and retain a perfect 90 blue flame throughout the whole range of 95 adjustment.

In said drawings 1 represents a lamp of the Argand or tubular wick type, having a font or bowl 2, surmounted by a burner 3 which carries a chimney 4 and is provided 100 with a mantle 5.

The burner comprises an outer casing 6, adapted to fit within and be supported by the top 7 of the font 2. This casing carries a centrally arranged wick 8, arranged between an inner wick tube 9 and an outer wick 105

tube 10. The wick is carried by a tubular member 11 having a vertical rack 12 by which the wick is adjusted as to height. For this purpose we provide the usual adjusting knob 13 and pinion 14 on the horizontal shaft 15.

The lower end of the casing 6 is closed by a horizontal plate 16, which is provided with openings 17 to admit air to the bowl of 10 the lamp, above the oil therein. The inner wick tube 9 is open at its lower end and air can rise therein from the lamp bowl. The upper end of the casing carries the chimney crown or holding member 18 which 15 is provided with a row of small air admission openings 19, adapted to admit a small quantity of air below the lower end of the chimney. The chimney holder is provided with spaced raised projections 20 to provide 20 a space below the lower end of the chimney to permit the air to enter. The projections 20 are formed in the floor 21 of the chimney holder which is imperforate.

The wick tubes 9 and 10 rise above the 25 floor 21 and surrounding the upper ends of these tubes is an outer cone 22, mounted concentric with the wick and connected solidly with the floor 21 of the chimney holder. This cone is contracted toward its upper 30 end 23 and terminates in an inwardly formed circumferential flange 24. The cone 22 and the floor 21 close the lower end of the chimney holder except for the small holes 19 and the central opening 25 of the 35 cone 22.

We do not depend for combustion upon any air which enters into the lower end of the chimney outside of the mantle 5, as we are enabled to cause complete and perfect 40 combustion of all burnable products within the mantle. We merely allow a little air to enter through the holes 19 to rise between the mantle and the chimney to assist in preventing the chimney becoming overheated.

45 We terminate the outer wick tube 10 at 26 somewhat below the flange 24, providing an annular space 27 for the flow of air up through or beneath the cone 22 to and into the flame above the wick.

50 We terminate the inner wick tube at 28, slightly above the end 26 of the outer tube, so that when the wick 8 is adjusted with its upper end 30 at the top of the inner tube, it will be burned to a curved contour 55 slightly higher at the inner edge than the outer edge as best shown in the enlarged view Fig. 4.

Both of these wick tubes are imperforate and to prevent the air which rises beneath 60 the cone 22 rushing too strongly over the outer edge or surface of the wick, we provide an external narrow circumferential flange 31 on the upper end 26 of the outer wick tube. The rising air has to circulate 65 around this flange and is then directed by

the cone 22 and the top flange 24 more horizontally against the upper end of the wick and into the flame. The flame 32 rises in the form of a cylinder above the wick and of greater or less height depending upon 70 the distance the upper end of the wick projects above the wick tubes.

While we are enabled to obtain thoroughly good results from our improved outer cone when the flange 24 is horizontal, we have 75 found that much greater efficiency and control of flame ensues when we depress the inner edge of the flange, making it, in fact, inclined downwardly to a slight extent, as best shown in Fig. 4. So far as we are informed, such flanges have heretofore been inclined upwardly, permitting the easy rise of the air from beneath the cone around the flame and not causing the direct and forced impingement of the air into the flame, which 80 we are enabled to accomplish. A further function which is inherent in this novel form of flange, especially in combination with the deflecting flange 31, is that of projecting the air downwardly upon the upper 85 end of the wick when the same is turned low.

At such times, the heat being generated is not very much and the consequent up-draft is small, very little if any air reaches 90 the wick from the inner tube and the result is that unless some means is provided which causes a forced application of air, combustion is not perfect and free carbon is produced. Furthermore, as the low flame is in 100 close contact with the inner tube at this time and, as stated, the draft is not strong, the heat of the flame is not carried away, and the inner tube is more highly heated than is desirable. This results in heat being 105 conveyed down the inner tube to the upper end of the wick, causing a quicker vaporization of the fuel, and a consequent rise in the flame. All of this results in a hot smoky flame which soon blackens the mantle, as 110 well as producing undesirable odors. All of these difficulties are eliminated by means of our improved burner, for it effects a better circulation of air, its direct impingement upon the upper end of the wick, with the 115 consequent perfect combustion and the rapid carrying away of the heat produced.

We can turn down our burner to a minimum flame and it will remain in such condition indefinitely, whereas heretofore it was 120 a practical impossibility to hold the flame at a minimum low point of adjustment.

The mantle 5 is carried by a holder 33 which fits the cone 22 adjacent to its base and is provided with a mantle carrying bail 125 34, which rises above the mantle and from which the mantle depends.

We close the upper end of the center or inner wick tube by a tubular air distributor 35. This distributor comprises a cylindri- 130

cal sleeve 36 fitting closely within the inner tube 9 and placed, as to relative height, by stops 37 provided on the inner surface of the tube 10, on which the lower end of the distributor rests. The lower end of the cylinder 36 is freely opened for the air to rise through same and we form it with a closed upper end 37'. The cylinder 36 is long enough so that its upper end rises a short distance above the flange 24 of the outer cone. The upper end is closed and we provide the cylindrical wall thereof with several rows of perforations 38, adjacent to the upper end and extending down close to the upper end of the inner wick tube. Preferably these rows of air holes in the wall of the distributor 36 are progressively enlarged toward the upper end of the distributor, the upper rows of holes being of larger diameter than the lower rows. Air can be fed directly against the inner surface of the upper end of the wick through the lower rows of these holes when the wick is adjusted above its lowermost position, the air entering the space 39 above the end of the inner wick tube 10, and between the wick and the distributor. But the upper rows of these holes are larger and of more value in directing air into the flame 32 above the upper end of the wick as best shown in Fig. 4. However, we do not depend upon this flow of air to the wick to effect the best admixture of air with the flame, we provide positive means for directing a flow or blast of air into and upon the flame from the inner side thereof and above the outer deflecting flange 24. This consists of an upper deflecting cone 40 on the top of the closed end 37' of the air distributor 36. This deflector cone comprises an annular upwardly and outwardly inclined flange secured at its inner edge or diameter upon the top 37' of the distributor 36. We preferably make the maximum diameter of the deflector nearly as great as the outer diameter of the air distributor 36, so that the outer edge of the flange 40 approaches close to the flame 32. Immediately beneath the flange 40 we provide an annular row of air holes 42 in the flat or horizontal upper end 37 of the air distributor 34 for causing the air to rise through the top 37' and be directed by the deflector into the flame, as best shown in Fig. 4.

The draft induced by the rising heated gases from the flame, draws the air down into the lamp bowl through the inlet openings 17 and up through the central inner wick tube 9 and up through the openings 42, where it strikes the under side of the deflector flange 40 and is positively directed into the flame, causing a perfect admixture of the air with the gases of combustion.

The flange 40 may be formed from or se-

65 in any suitable manner, such as producing a central projection 42 on the upper end 37 of a diameter to receive the flange 40, which is in the form of a ring, and then deforming the projection 42 downwardly upon the inner edge of the flange ring 40 to tightly secure the same in place. Other than the perforations 42 the upper end 37 of the distributor is imperforate.

70 By means of the inwardly extending flange 24 on the outer cone, the outwardly extending annular deflector 26 on the outer wick tube in combination with the inclined deflector 40 on the inner distributor, we are enabled to produce perfect combustion of the fuel at all points of adjustment of the flame; we are enabled to keep the burner cool when the flame is turned low, we are enabled to maintain the flame at any point of adjustment indefinitely, and we are enabled to produce a maximum of light with the use of a minimum quantity of fuel.

75 As many modifications of our invention will readily suggest themselves to one skilled in the art, we do not limit or confine our invention to the specific structures herein shown and described, except within the scope of the appended claims.

80 We claim:

85 1. In a lamp of the type described, having an inner wick tube, a spreader closing the upper end of the tube and rising above the upper end of the wick, the closed end of the spreader provided with an annular row of air outlet openings adjacent to its periphery, a cone deflector of substantially the same diameter as the spreader above said openings adapted to direct air rising therethrough substantially horizontally above the upper end of the wick.

90 2. A flame spreader for use in a tubular wick burner, comprising a cylindrical shell adapted to fit within the inner wick tube and having a closed upper substantially flat end, an annular row of air outlets in said end adjacent to the periphery thereof, and a substantially 45 degrees cone deflector on said upper end and above said outlets, adapted to deflect air outwardly which rises through said outlets.

95 3. In a burner of the tubular wick type having an inner wick tube, a straight cylindrical air controller in the upper end of the tube, air passages in the side walls of said controller above the tube, air passages through the top of said controller, and a circumferential baffle or spreader above the passages for forcing air issuing therefrom sideways into the top of the flame.

100 4. In a burner of the tubular wick type having an inner wick tube, a cylindrical air controller in the upper end of the tube, air passages in the side walls of said controller above the upper end of said tube and progressively increasing in size upwardly, air

passages in the top of said controller and a circumferential baffle or spreader above the passages through the top of the controller for forcing air issuing therefrom sidewise into the top of the flame.

5. In a burner of the tubular wick type having an inner and an outer wick tube, a burner cone having an internal annular deflecting flange at its upper end to direct air 10 inwardly into the flame, a cylindrical air controller in the upper end of the inner wick tube, air passages in the side walls of said controller above the inner tube, air passages through the top of said controller, and a circumferential baffle or spreader above the 15 passages through the top of the controller for forcing air issuing therefrom sidewise into the top of the flame.

6. In a burner of the kind described, having inner and outer wick tubes, a burner cone surrounding the wick, an internal annular deflecting flange at the upper end of the cone for directing air into the flame, a cylindrical air controller located in the upper end of the inner wick tube, said controller provided with air passages in its side walls above the upper end of the inner tube, said passages increasing in size progressively upward, the controller also provided

with air passages in its upper end, and an annular baffle or spreader, located above said last named passages to force air issuing therefrom sidewise into the top of the flame.

7. In a blue flame burner of the tubular wick type, an upwardly air directing flange 35 within the flame and a downwardly air directing flange outside the flame and arranged higher than the upwardly air directing flange.

8. In a blue flame burner of the tubular wick type, an air spreader within the wick rising above the wick and adapted to direct air upwardly into the flame, and a burner cone surrounding the wick and provided with a downwardly inclined flange above the air spreader and adapted to direct air downwardly into the flame at a point above the place where the upwardly directed air enters the flame.

In witness whereof I, AUGUST W. GREGOR, subscribe my name this 2nd day of May, A. D. 1918.

In witness whereof I, THEODORE H. FRENCH, subscribe my name this 29th day of April, A. D. 1918.

AUGUST W. GREGOR.
THEODORE H. FRENCH.
